Attorney

UNITED STATES PATENT OFFICE

OTHO V. KEAN, OF PROVIDENCE, RHODE ISLAND

SCRUBBING DEVICE

Application filed December 8, 1927. Serial No. 238,498.

This invention relates to an improved scrubbing device adapted for scrubbing and cleaning metal, glass and other surfaces to remove foreign matter adhering thereto.

5 One object of the present invention is to provide a device of this character adapted for use in cleaning metal, glass and other surfaces which is of a convenient shape for use in scrubbing and which is made entirely or substantially throughout of abrasive material whereby it will not become ineffective for the purpose through the elimination of the abrasive portion by reason of wear.

A further object is that of providing an article of this character capable of being readily and economically constructed and which will efficiently accomplish the purposes for which it is provided.

With these and further objects in mind reference is had to the annexed specification taken in connection with the drawings, which latter illustrate one practical embodiment of the invention and in which:—

Figure 1 is an elevational view of a tubular braided wire fabric, a portion thereof being shown in expanded condition, together with a mandrel or former which may be employed in expanding the wire mesh fabric.

Fig. 2 is a vertical sectional view of a portion of a tubular wire mesh fabric having one end thereof stitched together to form a sheath.

Fig. 3 is a perspective view, partially in section, of a sheath prepared for the reception of a pad and the pad prepared for insertion within the sheath.

Fig. 4 is a vertical longitudinal section of the completed scrubbing device, and,

Fig. 5 is a perspective view of the completed device.

In the embodiment of the invention illustrated herewith 1 designates a tubular metallic braid formed of metal strands or threads 2 which is made as a flat braid but which may be expanded to separate the threads or strands 2 from each other as indicated at 3 by drawing the tubular braid over a mandrel or former 4. The threads or strands 2 are provided with angular edges 5 which are adapted to exert an abrasive action upon surfaces to be

cleaned when the threads have been separated from each other after the manner described.

I propose to utilize the expanded tubular wire mesh, formed as above described, in the production of scrubbing devices adapted for use in cleaning metal, glass, or other surfaces and particularly kitchen utensils and the like, and for the accomplishment of this purpose I propose to provide a sheath formed by stitching together one end of a section 6 of the tubular wire mesh fabric as at 7 by means of a wire, thread or ordinary cord and then reversing the tubular section 6 to bring the stitching 7 within the sheath thus forming a sheath 8 for the reception of a suitable filler material for which I may employ a pad 9 constructed as will be more fully described hereinafter, although various other kinds and arrangements of filler material may be employed in forming the pad as will be apparent to those skilled in the art.

The pad 9, like the sheath 8, is formed in the present illustrated embodiment of the invention from a tubular expanded wire mesh constructed after the manner shown in Fig. 1 of the drawings.

The section of expanded tubular wire mesh fabric forming the pad may be of greater length than the section forming the sheath 8 and the open ends thereof are secured together as by stitches or loops 10, and wires or cords 11 located within the pad are employed to draw the opposite ends of the tubular section towards each other and thus form folds 12 in the pad as the fabric material is folded upon itself to increase the bulk of the pad. In assembling the parts to form the completed device the pad 9 is inserted within the sheath 8 and the ends of the cords or wires 11 are secured to the stitched ends of the sheath 8 by means of links or stitches 14 as shown in Fig. 4. The edge of the tubular material adjacent to the open end of the sheath is in-turned and stitched together as indicated at 15 to close the end of the sheath and form the completed scrubbing device 16. The cords or wires 11 hold the pad 9 against expansion as shown, and, when the ends of the wires are secured to the ends of the sheath by stitches 14 the wires 11 prevent longitudinal

expansion of the sheath which with braided tubular fabric as shown would result in decreasing the diameter of the sheath and thus altering the shape of the completed structure.

5 While I have shown the sheath 8 as being formed of a single section of the expanded tubular wire mesh fabric, I may employ two or more sections telescoped one within the other and with a common stitching for closing the end of the composite sheath. In like manner I may employ a plurality of tubular sections telescoped one within the other in forming the pad 9, or if desired the pad may be formed by flattening a section of the tubular wire mesh fabric and folding the flattened material upon itself to a sufficient extent to produce a pad of the desired thickness.

20 While I have described above a preferred form of my invention I may form the pad 9 partially of metallic wire mesh and partially of cloth or other suitable filler material, such, for example, as woven or unwoven metal strands or threads, or I may form the pad entirely of unwoven metal strands, threads, or other suitable abrasive material prepared in any desired manner without departing from the spirit and scope of my invention as defined by the appended claims.

30 It is to be understood also that the cords or wires 11 employed for holding the parts from undue expansion may be of any desired number, and may in certain cases, as where flatly folded tubular woven metal fabric material is employed in forming the pad, be connected with the opposite ends of the sheath, and may or may not be operatively connected with the ends of the pad.

What I claim is:

40 1. A scrubbing device comprising a pad of abrasive material, a cover therefor comprising a section of stretched wire mesh fabric arranged in the form of a tube over said pad, and means connecting opposite ends of said tube to limit the expansion of the same longitudinally.

50 2. A scouring device including a tube of resilient material disposed in the form of corrugations, means associated with said tube for maintaining such corrugations, and a sheath of flexible material enveloping such tube.

55 3. A scouring device including a tube of resilient material disposed in the form of corrugations, means associated with said tube for maintaining such corrugations, and a sheath of flexible metal fabric enveloping such pad and having its ends closed to retain the same.

60 4. A scouring device including a tube of resilient material disposed in the form of corrugations, means associated with said tube for maintaining such corrugations, and a sheath of flexible metal fabric enveloping such pad and having its ends closed to retain the same, and means associated with

said sheath and cooperating with the corrugation-maintaining means of said pad to retain the latter against substantial movement with respect to said sheath.

65 In testimony whereof I have affixed my signature. 70

OTHO V. KEAN.
